SHEET DELIVERY MECHANISM FOR
PRINTING PRESSES

Howard M. Barber, Pawcatuck, Conn., assignor to
C. B. Cottrell & Sons Company, Westerly, R. I.,
a corporation of Delaware

Application January 5, 1935, Serial No. 515

25 Claims. (Cl. 271—76)

In sheet feed rotary printing presses the product of the press is necessarily limited by the number of sheets which can be successfully delivered during a certain period. With the press running at high speeds it is difficult to successfully deliver the sheets flat in piles because of the trapping of air between the sheets in the piles. Various mechanisms have been proposed for solving this problem in an effective and reasonable manner.

My invention provides means whereby the sheets may be delivered flat to a plurality of piles with the press running at high speed, by bringing the sheets out over the piles and up to the front stops at a speed well below the surface speed of the impression cylinder.

My invention comprises a sheet delivery of the above character in which there is provided a sheet delivery rotary carrier arranged to take successive sheets from the impression cylinder at substantially the surface speed thereof, a sheet transfer endless chain carrier arranged to take the successive sheets from the sheet delivery rotary carrier at substantially the surface speed thereof, and a plurality of sheet delivery endless chain carriers arranged to take alternate sheets from the sheet transfer endless chain carrier at different points thereon and at a lesser surface speed, and then deposit the sheets on to their respective piles.

My invention further comprises manually controlled means for causing one of the sheet delivery endless chain carriers to deliver all of the sheets to its pile, when so desired.

A practical embodiment of my invention is represented in the accompanying drawings, in which

Figs. 1 and 1a represent diagrammatically in side elevation so much of a sheet feed multi-color printing press as will give a clear understanding of my improved flat sheet delivery mechanism, the parts being in the positions they assume when a sheet is being transferred from the sheet transfer endless chain carrier to the first sheet delivery endless chain carrier;

Fig. 2 represents a detail diagrammatic view showing the parts in the positions they assume when a succeeding sheet is being transferred from the sheet transfer endless chain carrier to the second sheet delivery endless chain carrier;

Fig. 3 represents a detail side view, partly in section, showing one of the sets of grippers on one of the sheet delivery endless chain carriers, taken adjacent to one of the side chains thereof;

Fig. 4 represents a similar view, taken adjacent to the other side chain;

Fig. 5 represents a transverse vertical section taken in the plane of the line V—V of Fig. 3;

Fig. 6 represents a transverse vertical section taken in the plane of the line VI—VI of Fig. 3; and

Fig. 7 represents a transverse vertical section taken in the plane of the line VII—VII of Fig. 4.

The impression cylinder is denoted by 1 and it is herein shown as being provided with two sets of diametrically opposed grippers 2 and 3. The form cylinders are denoted by 4, 5, 6 and 7, their gears 8, 9, 10, 11 being driven from the impression cylinder gear 12.

The sheet feed rotary carrier is denoted by 13 and it is shown as provided with a single set of 15 tumbler actuated grippers 14, the usual pins 15, 16 being provided for operating the tumbler gripper cam 17 to respectively take the sheets from the source of sheet supply 18 and transfer them successively to the grippers 2 and 3 of the impression cylinder 1. The sheet feed rotary carrier 13 is driven at substantially the surface speed of the impression cylinder through the gears 12 and 19.

The flat sheet delivery for the impression cylinder comprises the following elements:

The sheet delivery rotary carrier 20 is shown as being provided with a single set of grippers 21, the sheet delivery rotary carrier being driven at substantially the surface speed of the impression cylinder 1 through the gears 12 and 22.

A fixed cam 23 is provided for operating the impression cylinder grippers 2 and 3 at the proper times to take successive sheets from the sheet feed rotary carrier 13, said cam 23 also 35 coacting with a fixed cam 24 to transfer the sheets successively to the sheet delivery rotary carrier 20.

The sheet transfer endless carrier is denoted by 25 and may be of the well known side chain 40 type, provided with spaced transverse sets of grippers 26 mounted between the side chains of said sheet transfer endless carrier. Fixed cams 27, 28 are provided for operating the grippers 21 and 26 to cause the successive grippers 26 to 45 take successive sheets from the grippers 21 at a single point.

The upper and lower sheet delivery endless carriers 29 and 30 may also be of the well known side chain type and provided with spaced transverse sets of grippers 31 and 32 arranged to take alternate sheets from successive grippers 26 of the sheet transfer endless chain carrier 25 at different points along the same.

Interconnected movable cams 33 and 34 are 55

provided for transferring alternate sheets from the grippers 26 of the sheet transfer endless chain carrier 25 to the grippers 31 of the upper sheet delivery endless chain carrier 29. These cams 33 and 34 are connected by rods 35 and 36 to the arms 37, 38 of a rock lever, the other arm 39 of which is connected to one end of a rod 40, the other end of which rod carries a stud or roller 41 operated by a cam 42 fast on the shaft 10 43 of the impression cylinder 1. The stud or roller 41 may be held against the face of its cam 42 by a spring 44 interposed between a fixed bracket 45 and a collar 46 fast on the rod 40.

Fixed cams 47, 48 are arranged in position to transfer alternate sheets from the grippers 26 of the sheet transfer endless chain carrier 25 to the grippers 32 of the lower sheet delivery endless chain carrier 30.

Fixed cams 49 and 50 are arranged in position to open the grippers 31 of the upper sheet delivery endless chain carrier 29 and the grippers 32 of the lower sheet delivery endless chain carrier 30 to deliver the sheets on to the piles 51 and 52 respectively.

The sheet transfer endless chain carrier 25 is driven at substantially the surface speed of the sheet delivery rotary carrier 20 and the impression cylinder 1. The upper and lower sheet delivery endless chain carriers 29 and 30 are driven at a considerably lesser surface speed than the sheet transfer endless chain carrier 25. This may be accomplished as follows:

The shaft 53 of the sprocket wheels 54 which drive the upper sheet delivery endless chain carrier 29 is driven from the impression cylinder gear 12 through the train of gears 55, 56, 57, 58, 59. The shaft 60 of the sprocket wheels 61 which drives the lower sheet delivery endless chain carrier 30 may be driven from the gear 59 through the gears 62, 63. The shaft 64 of the sprocket wheels 65 which drive the sheet transfer endless chain carrier 25 may be driven from the shaft 60 through the gears 66 and 67.

The several sets of grippers on the sheet transfer and sheet delivery endless chain carriers are alike and therefore a particular description of one only of the sets of grippers will suffice, for instance, the set of grippers 31 on the upper sheet delivery endless chain carrier 29. A crossbar 68 is mounted at its ends in the side chains of the endless carrier, along which crossbar at spaced intervals the relatively fixed jaws 69 of the set of grippers 31 are clamped. A rocking crossbar 70 is mounted at its ends in ears 71 projecting laterally from the fixed crossbar 68, along which rocking crossbar 70 at spaced intervals the movable jaws 72 are clamped in position to contact with their respective fixed jaws 69. The movable jaws 72 are yieldingly held closed by a spring pressed rocking lever 73 fast on the rocking crossbar 70, said lever having a projection 74 engaging the bracket 75 on the fixed crossbar 68, between which bracket and the lever 73 the expansion coil spring 76 is interposed. At one end of the rocking crossbar 70 an arm 77 is provided, which arm carries a stud 78 arranged in position to be engaged by its cams for controlling the operation of the grippers.

I have provided manually controlled means for holding the movable cams 33 and 34 stationary in their operative position so that all of the sheets may be transferred from the sheet transfer endless chain carrier 25 to the upper sheet delivery endless chain carrier 29 for delivery on to the outer pile 51, for inspection purposes, or,

when starting the press, to facilitate the removal of all imperfect sheets. This may be accomplished by providing a manually operated lever pivoted at 79, said lever having one arm 80 connected to a rod 81 leading to a convenient point for manual manipulation, and another arm 82 arranged in position to be swung into engagement with the collar 46, which acts as a stop on the connecting rod 40, to prevent the stud or roller 41 from following the contour of the cam 10 42 on the shaft 43 of the impression cylinder.

From the above description it will be seen that I have provided simple and effective means whereby the sheets may be taken by the grippers on the upper and lower sheet delivery endless chain carriers 29 and 30 alternately from the grippers 26 on the sheet transfer endless chain carrier 25 at a lesser surface speed than the said sheet transfer endless chain carrier 25, thus rendering it possible to run the printing press 20 at high speeds and yet successfully deliver the sheets flat in piles, time being permitted for the proper settling of the sheets on their respective piles.

This application is a continuation in part of 25 my application, Serial No. 725,692, filed May 15, 1934.

It is evident that various changes may be resorted to in the construction, form and arrangement of the several parts without departing from the spirit and scope of my invention, and hence I do not intend to be limited to the particular embodiment herein shown and described, but

What I claim is:

1. In a sheet feed rotary printing press, an 35 impression cylinder and a sheet transfer endless chain carrier, both traveling at substantially the same surface speed, and a plurality of sheet delivery endless chain carriers traveling at a lesser surface speed and arranged to take alternate 40 sheets from the sheet transfer endless chain carrier at said lesser surface speed.

2. In a sheet feed rotary printing press, an impression cylinder and a sheet transfer endless chain carrier, both traveling at substantially the 45 same surface speed, and a plurality of sheet delivery endless chain carriers traveling at a lesser surface speed and arranged to take alternate 50 sheets from the sheet transfer endless chain carrier at different points thereon and at said lesser surface speed.

3. In a sheet feed rotary printing press, an impression cylinder, a sheet delivery rotary carrier and a sheet transfer endless chain carrier, all traveling at substantially the same surface speed, 55 and a plurality of sheet delivery endless chain carriers traveling at a lesser surface speed and arranged to take alternate sheets from the sheet transfer endless chain carrier at said lesser surface speed.

4. In a sheet feed rotary printing press, an impression cylinder, a sheet delivery rotary carrier and a sheet transfer endless chain carrier, all traveling at substantially the same surface speed, 65 and a plurality of sheet delivery endless chain carriers traveling at a lesser surface speed and arranged to take alternate sheets from the sheet transfer endless chain carrier at different points thereon and at said lesser surface speed.

5. In a sheet feed rotary printing press, an impression cylinder, a sheet delivery rotary carrier and a sheet transfer endless chain carrier, all traveling at substantially the same surface speed, 70 their coacting sets of grippers, a plurality of sheet delivery endless chain carriers traveling at a 75

- endless carriers arranged to take alternate sheets from the sheet transfer endless carrier at different points thereon.
21. In a sheet feed rotary printing press, an impression cylinder and a flat sheet delivery therefor comprising a sheet delivery rotary carrier operable to take successive sheets from the impression cylinder at a single point, a sheet transfer endless carrier arranged to take successive sheets from the sheet delivery rotary carrier at a single point, a plurality of sheet delivery endless carriers arranged to take alternate sheets from the sheet transfer endless carrier at different points thereon, means for driving the sheet delivery rotary carrier and the sheet transfer endless carrier all at substantially the same surface speed as the impression cylinder and means for driving the sheet delivery endless carriers at a lesser surface speed. 10
22. In a sheet feed rotary printing press, an impression cylinder having two sets of diametrically opposed grippers, a sheet feed rotary carrier for feeding successive sheets to said impression cylinder grippers, a sheet delivery rotary carrier having a single set of grippers arranged to take successive sheets from the impression cylinder grippers at a single point, a sheet transfer endless carrier having sets of grippers arranged to take successive sheets from the sheet delivery rotary carrier grippers at a single point and a plurality of sheet delivery endless carriers having sets of grippers arranged to take alternate sheets from the sheet transfer endless carrier grippers at different points. 20
23. In a sheet feed rotary printing press, an impression cylinder having two sets of diametrically opposed grippers, a sheet feed rotary carrier for feeding successive sheets to said impression cylinder grippers, a sheet delivery rotary carrier having a single set of grippers arranged to take successive sheets from the impression cylinder grippers at a single point, a sheet transfer endless carrier having sets of grippers arranged to take successive sheets from the sheet delivery 30
- rotary carrier grippers at a single point, a plurality of sheet delivery endless carriers having sets of grippers arranged to take alternate sheets from the sheet transfer endless carrier grippers at different points thereon, means for driving the sheet delivery endless carriers at a lesser surface speed. 35
24. In a sheet feed rotary printing press, an impression cylinder and a flat sheet delivery therefor comprising a sheet delivery rotary carrier operable to take successive sheets from the impression cylinder at a single point, a sheet transfer endless carrier arranged to take successive sheets from the sheet delivery rotary carrier at a single point and a plurality of sheet delivery endless carriers arranged to take alternate sheets from the sheet transfer endless carrier at different points thereon and manually controlled means for causing one of the sheet delivery endless carriers to take all of the sheets from the sheet transfer endless carrier. 40
25. In a sheet feed rotary printing press, an impression cylinder having two sets of diametrically opposed grippers, a single sheet feed rotary carrier for feeding successive sheets to said impression cylinder grippers, a sheet delivery rotary carrier having a single set of grippers arranged to take successive sheets from the impression cylinder grippers at a single point, a sheet transfer endless carrier having sets of grippers arranged to take successive sheets from the sheet delivery rotary carrier grippers at a single point and a plurality of sheet delivery endless carriers having sets of grippers arranged to take alternate sheets from the sheet transfer endless carrier grippers at different points thereon and manually controlled means for causing one of the sheet delivery endless carriers to take all of the sheets from the sheet transfer endless carrier. 45

HOWARD M. BARBER.
